UNITED STATES PATENT OFFICE.

ALFRED WILD, OF MILWAUKEE, WISCONSIN.

WEAVING-MACHINE.

REISSUED

1,386,826.

Specification of Letters Patent.

Patented Aug. 9, 1921.

Application filed November 19, 1919. Serial No. 339,147.

To all whom it may concern:

Be it known that I, ALFRED WILD, a citizen of the present Government of Czechoslovakia, and resident of Milwaukee, in the 5 county of Milwaukee and State of Wisconsin, have invented new and useful Improvements in Weaving-Machines, of which the following is a description, reference being had to the accompanying drawings, which 10 are a part of this specification.

The present invention relates to certain new and useful improvements in weaving machines and refers more particularly to a machine of this type especially adapted for 15 use in weaving baby carriage bodies, hoods and any other goods made of reed, fiber or any other materials.

Heretofore it has been the general custom to weave the material and then cut the 20 woven material into shape and tack the same upon a body form or else to weave the same by hand upon the body form. This manner of constructing baby carriage bodies is unsatisfactory in that the same is 25 very expensive necessitating the work of several men for each body and necessitating an unnecessary amount of time in construction.

With these and other inherent objections 30 in mind my invention has for its primary object to provide a body weaving machine which will weave the complete body direct upon the body core or form and which will be automatic and require the attention of 35 but one operator, thereby greatly reducing the cost of production as well as decreasing the amount of time at present necessary to produce a completed baby carriage body.

Another object of this invention is to 40 provide a baby carriage body weaving machine which may be entirely automatic in its operation and which may be manually operated if it is so desired.

A further object of the present invention is to provide a baby carriage body weaving machine which will operate with either reed, fiber, or any other desired material without breakage as the warp guiding tubes which extend to a point adjacent the 50 topmost weft insures the smooth operation of the upper filling strand or weft being interwoven irrespective of the roughness of the warp.

A still further object of the present invention is to provide means for pressing the weft into place after the same has been in-

terwoven between the warp and to also provide means for mechanically or electrically operating the warp carrying guide tube members as hereinafter described.

60

With the above and other objects in view which will appear as the description proceeds, my invention resides in the novel construction, combination and arrangement of parts, substantially as herinafter described and more particularly defined by the appended claims, it being understood that such changes in the precise embodiment of the hereindisclosed invention may be made as come within the scope of the claims.

70

In the accompanying drawings I have illustrated two complete examples of the physical embodiment of my invention constructed according to the best modes I have so far devised for the practical application 75 of the principles thereof, and in which:

Figure 1 is a side plan view of a baby carriage body weaving machine embodying the features of my invention.

Fig. 2 is a top plan view thereof.

80

Fig. 3 is a sectional view taken transversely through one arm of the supporting frame on the line 3—3 of Fig. 2.

Fig. 4 is a fragmentary detail view taken on the plane indicated by the line 4—4 of 85 Fig. 3.

Fig. 5 is a partly diagrammatic view illustrating my invention as adapted for operation by a plurality of electric magnets, and

Fig. 6 is an enlarged detail view of one 90 of the block members.

Referring now more particularly to the accompanying drawings, the numeral 10 indicates a substantially U-shaped supporting frame consisting of two spaced channel 95 members 11 having their ends secured to a pair of supporting posts or standards 12. The frame 10 may be of various shapes according to the type for which it is especially designed and has mounted thereon two series of block members 13 secured to the top face of the channel irons 11 by suitable fastening means 14, see Fig. 3.

The inner ends of the blocks 13 of each series are arranged in spaced relation to 105 provide an intermediate channel 15 extending around the frame and normally disposed centrally of the channel 15 are a plurality of warp guide tube carrying members 16. One warp guide tube carrying member 110 16 is carried by each adjacent pair of blocks 13 of the two series and is movable

out of the channel 15 into a recess 17 formed in each block 13, as will be later described.

Each block 13 is centrally bored as at 18 and has disposed therein a spring guide 5 rod 19 having its outer end enlarged as at 20 and disposed outwardly of the block and its inner end disposed within the recess 17, and having a washer or collar secured thereto between which and the outer wall of 10 bore 18 a spring 21 is confined. By this structure the member 16 is normally urged to a position centrally of the channel 15 as will be at once seen, the head 20 preventing the rod 19 or spring 21 of one block 15 from projecting into the channel 15 when the member 16 is urged into the recess 17 of the adjacent opposed block by the means to be later described.

In operation a flat woven portion of ratan 20 members woven together and preferably secured to a board (not shown) used as a base member which is in turn secured to the under side of a body form of core 22 which is then mounted upon the top of a jack 25 screw 23 adjustably carried by a tubular supporting standard 24 and is engaged by a threaded nut 25 provided with peripheral ratchet teeth 26 for automatically lowering the jack screw and consequently the body 30 22, as will be later described. The warps 27 of the flat woven material secured to the underside or bottom of the core 22 are disposed within warp guiding tubes 28 having their upper ends secured to the members 16. The guide tubes 28 have flexible portions 29 adjacent their point of connection with the members 16 whereby the movement thereof is unhindered.

Disposed about the inner series of blocks 40 13 is a track 30 shaped to correspond with that of the frame 10 to the inner channel 11 on which it is secured by bracket arms 31, see Fig. 3. Movable mounted on the track 30 is an operating motor 32 mounted upon a 45 support 33 in which is mounted a horizontal shaft 34 in gear connection with the motor 32 and a vertical shaft 35 in gear connection with the shaft 32. Freely journaled upon the shaft 35 are two sets of guide wheels 37 50 and 38, the wheels 37 engaging the outer face of the track 30 and the wheels 38 engaging longitudinal edges thereof, and two guide wheels 39 engage the rear face of the track 30 and thus freely movably mount the support 33 upon the track.

In order that the carriage 33 may be moved about the frame 10 a gear pinion 40 is fixed upon shaft 35 and is in mesh with a gear rack 41 secured to the outer face of the track 30. 60 Secured to the carriage 33, as at 42, is an arm 43 which projects over the channel 15 between the sets of blocks 13 and has mounted therein the upper end of a weft guide tube 44 which extends downwardly to a point adjacent the lower ends of the warp guide tubes

28. The guide tube 44 is capable of a slight lateral swinging movement by reason of the flaring opening 45 in which it is secured but is rigid against the longitudinal swinging movement.

Secured to the housing of motor 32 is a supporting shaft 46 for a drum or spool 47 upon which is wound the weft 48 which extends downwardly through the guide tube 44 and is interwoven between the warp 27 in 75 the manner hereinafter described.

Each member 16 has a roller 49 journaled on its upper base having a central aperture therein communicating with the guide tube 28 which rollers are adapted to be engaged by a cam member 50 which is journaled upon the weft guiding tube 44. The cam 50 is adapted to be rocked by means of a pitman or connecting rod 51 having one end secured to the cam member as at 52 and its other end secured to a crank pin 53 carried by a disk or wheel 54 mounted upon the lower end of the shaft 35.

From the foregoing description taken in connection with the accompanying drawings 90 it will be apparent that as the carriage 33 moves along the track 30 the cam 50 is rocked causing its leading pointed end 50' to move the adjacent member 16 in one direction as for example, to the left, and as the carriage 95 is advanced the distance between the blocks the member 16 which has been moved to the left will then be engaged by the rear end 50' of the cam and the next member 16 will be moved to the right. With the warps 27 100 which are carried by the members 16 by their guide tubes 28 the weft 48 is laid between the warps and as the carriage 33 progresses the members 16 are alternately moved first in one direction and then in another.

When the carriage 33 has reached one end of the track 30 it is reversed and travels back over the track again alternately moving the members 16 in opposite directions and disposing the weft therebetween to accomplish 105 the weaving as will be obvious.

In order that the weft 48 will alternately engage the opposite sides of each warp, I employ an uneven number of warps and the effect will be that each end warp will have the weft coiled thereon. In order to insure the topmost weft engaging the warp thereunder I provide a presser finger or wheel 56 which is carried by the carriage 33 or the guide tube 44 and presses the same down as best shown 115 in Fig. 1.

As it is necessary to drop or lower the core 22 the distance of the thickness of the weft after each complete operation of my device I provide a bell crank lever 57 pivoted to the standards 12 and having its lower end engaged with a slidably mounted bar 58 having a dog 59 engageable with the ratchet teeth 26 of the nut 25, the upper ends of arms 60 formed on said bell crank lever are en- 125 130

gagable by the carriage 33 when it reaches either limit of movement to rotate the nut 25 and consequently lower the core 22.

At each end of the track 30 I provide a stop 61 to prevent the carriage 33 from running thereoff, and said stop has a reversing switch 62 carried thereby for reversing the direction of rotation of the motor 32 when the carriage engages the stop, and as this specific structure forms no important part of my invention except in the combination set forth, the same has only been shown without its electric connections.

In place of the cam 50 for moving the members 16 in opposite directions to accomplish the weaving of the weft with the warps, I may employ electromagnets 63 as best shown in Fig. 5, the magnets of every other block 13 of one series having their positive ends connected by a wire 64 with a switch 65 disposed at one end of the track 30 and the negative ends of the magnets of the blocks 13 opposite the members as having their positive ends connected by wires 64 are connected by a wire 66 leading to another point of the switch 65. The positive ends of the magnets intermediate the magnets having their negative ends connected by the wire 66 are connected by a wire 67 with the wire 64 and the negative ends of the magnets opposite the magnets having their positive ends connected by a wire 67 are connected with the wire 66 by a wire 68. By this construction the members 16 will be staggered as depicted in Fig. 5 when the switch 65 is closed and thus the carriage 33 may be run around the frame 10 at a greater speed than with the structure hereinbefore described and when the same reaches the end of the frame opposite the end 40 having a switch 65 the same engages a switch similar to switch 65 (not shown) reversing the connections with the magnets 63 and oppositely staggering the members 16 so that the carriage 33 may run around the frame 45 and dispose the weft 48 properly between the warps.

From the foregoing description taken in connection with the accompanying drawings, it will be at once apparent that I provide a comparatively simple machine for weaving baby carriage bodies or the like and that by providing the guide tubes 28 for the warps the same may be employed for any kind of material as the warps 38 have their outer ends smooth and thus no friction is caused by the weft sliding therebetween. It will also be seen that I weave direct upon the body form whereas heretofore the material has been woven separately and then shaped and placed over the body form.

What I claim for my invention is:

1. A machine of the class described, comprising a supporting frame, a plurality of warp carrying members carried thereby, spring means yieldably holding said mem-

bers in a mid position, a weft carrying member mounted to travel along the frame, means for moving the weft carrying member along the frame, and means carried by the weft carrying member for moving said warp carrying members transversely from mid position to stagger the same whereby weft carried by said weft carrying member may be interwoven between the warps carried by the warp carrying members. 75

2. A machine of the class described, comprising a supporting frame, a plurality of warp carrying members carried by said frame, a supporting track carried by said frame, a carriage member mounted to travel back and forth on said track, a weft carrying member carried by said carriage member, means for moving said carriage along the frame, means mounted on said weft carrying member and operable as said carriage is moved along the frame for staggering the warp carrying members whereby weft carried by said weft carrying members may be interwoven between the warps. 85

3. A weaving machine comprising a supporting frame, a plurality of tubes forming warp carrying members carried by the supporting frame, a weft carrying member mounted to travel along the supporting frame, and means for staggering the warp carrying members whereby weft carried by said weft carrying member may be interwoven between the warps carried by said warp carrying members. 90

4. A machine for weaving bodies comprising a substantially U-shaped supporting frame, a plurality of warp carrying members carried by the supporting frame, a weft carrying member movable along the supporting frame, means for moving weft carrying members along the supporting frame in one direction, means for staggering the warp carrying members and the warps carried thereby upon such movement of the weft carrying member whereby the weft carried by the weft carrying member may be interposed between the warps, means for automatically reversing the direction of movement of the weft carrying member along the frame upon its reaching its limit of movement, and means for reversing the staggering of the warp carrying members upon reverse movement of the weft carrying member. 115

5. A weaving machine comprising a supporting frame, a body form disposed beneath the supporting frame, a plurality of warp carrying members carried by the supporting frame and disposed against the sides of the body form, and means traveling along the supporting frame for interweaving a weft between the warps carried by the warp carrying members. 120

6. A weaving machine comprising a supporting frame, a body form disposed beneath the supporting frame, an adjustable 130

support for the body form, a plurality of warp carrying members carried by the frame and having warps disposed against the body form sides, a weft carrying member movable around the frame for interweaving a weft with the warps carried by the warp carrying members, and means for operating said adjustable support after the weft carrying member has completed one movement 10 around said frame, whereby the body form will be lowered.

7. A weaving machine comprising a supporting frame, a body form disposed therebeneath, warp carrying members mounted 15 on the frame and having warps disposed against the body form sides; a track disposed above the warp carrying member, a weft carrying member mounted on the track, and means for interweaving a weft carried by 20 said weft carrying member with the warps.

8. A weaving machine comprising a supporting frame, two series of spaced blocks carried thereby, warp carrying members carried by the adjacent blocks of the series and 25 normally disposed in the space therebetween, a weft guiding tube movable along the space between said series, and means mounted on said weft guiding tube for moving adjacent warp carrying members in opposite directions.

9. A weaving machine comprising a supporting frame, two series of spaced blocks

carried thereby, warp carrying members carried by the adjacent blocks of the series and normally disposed in the channel formed 35 between the series, a warp guide tube carried by each of said warp carrying members, a carrier movable about said supporting frame, a weft guiding tube carried thereby and projected downwardly through the 40 channel between the series of blocks, and means mounted on said weft guiding tube for moving adjacent warp guiding members in opposite directions out of said channel.

10. A weaving machine comprising a supporting frame, two spaced apart series of blocks secured thereto, said blocks having their inner faces recessed, a warp guide tube carrying member carried by each adjacent pair of blocks and movable into the recess 50 of either block, a track mounted about the supporting frame, a carrier mounted on said track and movable therealong, a weft guide tube carried by said carrier and projected downwardly between the series of blocks, 55 and means mounted on said weft guide tube and engageable with said warp guide tube carrying members whereby said warp guide tube carrying members are moved into the recesses of the blocks as the guide tube is 60 moved through the space between the series of blocks.

In testimony whereof I affix my signature.
ALFRED WILD.
